UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

WELT-SHOE.

1,137,270.

Specification of Letters Patent. Patented Apr. 27, 1915.

Application filed May 20, 1911, Serial No. 626,379.

To all whom it may concern:

Be it known that I, FRANK W. MERRICK, a citizen of the United States, residing at Boston, in the county of Suffolk, State of Massachusetts, have invented a certain new and useful Improvement in Welt-Shoes, of which the following is a specification, reference being had therein to the accompanying drawings.

10 The present invention consists in a novel and improved welt shoe which bears a resemblance structurally to shoes of the Goodyear welt type in that it has a welt which is attached by means of an inseam to an upper and an insole, and to which an outer sole is attached by means of an out-seam. It has the appearance and all of the desirable characteristics of a shoe of the said type, including the snug fit, shapeliness, and durability 15 thereof, while at the same time it is so constructed as to be free from certain drawbacks of shoes of the said type as heretofore made, and is an improvement upon such shoes. It possesses the ease and comfort, and the 20 smooth and flexible tread of a shoe of the stitchdown type.

My improved and novel construction simplifies the operations of manufacture, reduces the number of operations, and dispenses with all occasion for the employment of certain machines and parts of machines at present in use in the manufacture of Goodyear welt shoes. It secures certain results which are not secured in shoes of the 25 Goodyear welt type as at present manufactured, or in shoes of any other type.

Briefly stated, in making a welt shoe embodying my invention, I produce an insole by taking a thin flexible insole-blank and forming an upstanding edge-flange or lip thereon by a bend around the margin of the said blank defining the extreme outer boundary of the tread-surface of the insole, and with a continuation of the tread-surface 30 forming the exterior of the flange or lip adjacent the bend. I then apply the prepared insole to the central portion of the tread-surface of a last, with the marginal portion of the latter tread-surface projecting outwardly beyond the outer margin of the tread-surface of the insole. I apply an upper to the last and bend it around the edge of the last, drawing it inward upon the exposed marginal portion of the tread-surface 35 of the last to and against the said con-

tinuation of the insole tread-surface immediately at the bend. I then apply a welt, stitch the inseam, trim the inseam, apply an outsole, and connect the outsole with the 60 welt by an outseam.

In the practice of my invention I usually make the insoles of cloth, which is not adapted to be channeled or split to form a feather and a lip or shoulder to receive the stitches of an inseam, or of thin flexible material lacking the thickness requisite to permit the channeling or splitting. This choice of materials conduces to great flexibility and pliability of the finished shoes, and permits a material saving in cost. The insole forming a portion of my improved shoe has no feather continuing the tread-surface of the 65 insole outward beyond the edge flange or lip which receives the inseam-stitches.

In order to secure an underset inseam with 70 the upper over-hanging and bulging outward past the inseam so as to give the proper shape and appearance to the shoe, I employ in making my shoe a last having a rounded or chamfered marginal reduction around the 75 tread-surface of its sole. The said marginal reduction or chamfer is located inward relative to the lateral bulging body of the last, so that after the insole has been applied to the central portion of the sole of the last, 80 and the upper has been applied to the last, the operation of drawing the upper inward to the flange or lip of the insole will bend the upper inward around the exposed rounded or chamfered margin of the sole, and the 85 marginal reduction of the last will afford the necessary clearance to enable the stitch-forming devices of the sewing machine by which the inseam is stitched to form the inseam at a point inwardly-located upon the 90 tread-surface of the sole of the last.

The invention is illustrated in the drawings, in which,—

Figure 1 shows in perspective the insole with its molded flange. Fig. 2 is a view thereof in cross-section on line 2, 2, of Fig. 1. Fig. 3 shows in vertical cross-section an upper containing a last, and having combined therewith the insole of Figs. 1 and 2 and a welt, the said welt and the upper being attached 100 to the molded flange of the insole by a line of stitches constituting the inseam. Fig. 4 shows the parts of Fig. 3 after the margins 105 of the welt, upper and molded flange of the insole have been trimmed away close to 110

the inseam. Fig. 5 shows the parts after the outer sole and cushion or filler have been combined therewith, with the outer sole connected to the welt by the outseam.

5 Referring to the drawings,—As above referred to, I subject the blank for the insole 1 to an operation by which its marginal portion is molded to form the upstanding flange 2. The angle which the flange is caused to 10 assume with relation to the plane of the tread-surface of the insole may vary in practice. In producing the insole, I take a blank of proper size, of a thin flexible material, and form the flange thereon by a simple 15 bending of the marginal or edge-portion of the blank so as to cause it to stand at the required angle to the said plane, and by means of the bending operation I cause the flange to become set in the desired position. 20 The insole thus prepared has no so-called feather, and the outer face of the flange is a continuation of that surface of the body-portion, *i. e.*, intermediate portion of the insole, which in the lasting operation faces the 25 sole of the last 4, and which during the wearing of the shoe receives the direct pressure of the wearer's foot.

In Figs. 3, 4, 5, the upper is marked 3, and 4 is the last within the upper, 5 being 30 the welt. A lining is indicated at 10. I apply the prepared insole of Figs. 1 and 2 to the last 4 as in Fig. 3, draw the upper and lining inward around and over the margin of the last, and place the margins of 35 the upper and lining directly against the outer surface of the molded flange 2, as in Fig. 3. I also place a welt 5 against the exterior of the upper as in said figure, and secure the welt, upper, lining, and flange of 40 the insole together by a line of stitching 6 passing through the entire thickness of the flange and located close to the angle or bend of the latter, thereby forming the inseam, the result being as shown in Fig. 3. The 45 flange serves as a guide during the stitching operation, and preserves or maintains the regularity of the stitching. I then trim off the margins of the welt, upper, lining, and molded insole-flange close to the inseam, as 50 in Fig. 4, after which I flatten out the welt so as to cause it to stand out. I then apply a cushion 7 to the exposed outer surface of the insole, within the trimmed molded flange, and next apply an outer sole 8, 55 fastening said outer sole to the welt by means of stitches 9 passing vertically through the welt and the sole 8 and constituting the out-seam.

As a result of making the insole with a 60 molded flange as aforesaid by a simple bending operation without channeling into or splitting the thickness of the insole along the line of the bend to form a feather and lip I am enabled to employ a thin insole 65 of any convenient and suitable tough and

flexible material, such, for instance, as cloth, which would not permit a cutting or channeling operation. Soft or chrome-tanned leathers may also be employed. By forming the flange by bending the insole, without 70 channeling or splitting, I am enabled to retain the entire strength of the material of the insole without diminution in the flange, and to get the benefit of the toughness of the grain side of the leather when that remains on the insole-blank, the grain being 75 the toughest portion of the leather.

In dispensing with the usual operation of channeling the insole to form a lip and a feather I omit the feather altogether, but 80 nevertheless I attain the same overhang of the upper of the shoe that heretofore has necessitated the formation of a feather upon the insole of a welt sole. My improved construction renders unnecessary the employment of channel-openers and the like in the 85 sewing machine by which the inseam is sewed. It allows the use of an insole of extremely flexible material. The omission of a feather secures in the completed shoe the 90 advantage that there is nothing to form a ridge beneath the wearer's foot, and to curl out of shape and hurt the foot.

I have stated above that the flange of the insole serves as a guide during the stitching 95 operation, and preserves or maintains the regularity of the stitching. The stitching is gaged from the inner angle of the bend of the flange with relation to the body of the insole, and the upper and lining are held 100 close against the outer surface of the flange, thereby securing regularity in the shape of the shoe.

A shoe embodying my invention has extreme flexibility in the sole thereof, attained by so shaping the insole as to permit a firm inseam to be secured on stock that is unfitted or too thin to be channeled. The shoe is absolutely smooth inside, inasmuch as the edge of the insole is so secured to the 110 welt and upper that the margin of the sole cannot turn up, in course of drying after being moistened, to form a ridge to hurt the wearer's foot.

In some cases, in practice, I cut through 115 the flange 2 of the insole at the points *x*, *x*, Fig. 1, cut away the portion of the said flange at the rear of the said points, around the heel-portion of the insole, insert a counter-stiffener in place, turn the flange of the 120 latter into position, and last the heel-portion of the shoe in the same way as any ordinary shoe is lasted.

I claim as my invention,—

1. The improved welt-shoe having an insole of thin flexible material formed with a permanent inseam-governing molded down-turned edge-flange or lip produced by a bend around the margin thereof defining the extreme outer boundary of the tread-surface 125 130

of the insole and controlling the position of the inseam and the shape of the shoe, said shoe also having the upper drawn inward against the said continuation of the insole 5 tread-surface immediately at the bend, a welt, an inseam securing the welt, upper and flange or lip together, and an outsole secured to the welt by an outseam.

2. The improved welt-shoe having an in-
10 sole of thin flexible material formed with a permanent inseam-governing molded down-turned edge-flange or lip produced by a bend around the margin thereof defining the extreme outer boundary of the tread-surface
15 of said insole and controlling the position of the inseam and the shape of the shoe, with

the whole substance of the insole extending to the said boundary, and a continuation of the said tread-surface forming the exterior of the flange or lip, said shoe also having 20 the upper drawn inward against the said continuation of the insole tread-surface immediately at the bend, a welt, an inseam securing the welt, upper, and flange or lip together, and an outsole secured to the welt by 25 an outseam.

In testimony whereof I affix my signature in presence of two witnesses.

FRANK W. MERRICK.
